RAILWAY BRAKING APPARATUS

Harold C. Clausen, Wilkinsburg, Pa., assignor to
The Union Switch & Signal Company, Swiss-
vale, Pa., a corporation of Pennsylvania

Original application June 16, 1936, Serial No.
85,506. Divided and this application April 14,
1937, Serial No. 136,866

6 Claims. (Cl. 188—62)

My invention relates to railway braking apparatus, and particularly to that class of railway braking apparatus known as car retarders. More particularly, my present invention relates to car retarders of the type in which the braking bars exert a fixed amount of retardation on all cars passing through the retarder.

One object of my invention is to provide a car retarder of the type described in which the couple caused by the forces which urge the braking bars into engagement with the wheels of cars which are being retarded, and the reaction of the wheels against the braking bars, is counteracted by a structure which is secured to the braking bars.

Other objects of my invention will appear as the description proceeds.

The present application is a division of my co-pending application, Serial No. 85,506, filed on June 16, 1936 for Railway braking apparatus.

I shall describe one form of car retarders embodying my invention, and shall then point out the novel features thereof in claims.

In the accompanying drawings, Fig. 1 is a vertical sectional view showing one form of car retarder embodying my invention. Fig. 2 is a top plan view of the retarder shown in Fig. 1.

Similar reference characters refer to similar parts in each of the several views.

Referring to the drawings, the reference character 1 designates one track rail of a stretch of railway track, which track rail is mounted on rail supports 2 secured to the usual crossties 3, only one rail support and one crosstie being shown in the drawings. Extending parallel to the rail 1 on opposite sides of the rail are two braking bars A¹ and A², each comprising a brake shoe 4 secured to a brake beam 5. The brake shoes and brake beams may have any desired cross sectional shape possessing the necessary strength and rigidity, but as here shown, the brake shoes are L-shaped in cross section, while the brake beams are H-shaped in cross section.

The braking bars are slidably supported for movement toward and away from the rail 1 by means of a pair of eyebolts 40 which extend with clearance through holes 8 provided in the web of the rail 1, and through holes 9 provided in the depending legs of the brake beams 5 of the braking bars. The threaded ends of the eyebolts 40 are secured to the brake beam 5 of the braking bar A¹ by means of nuts 40^a, while the eyes of the eyebolts are mounted on the opposite ends of a pin 41 which extends horizontally through the rear portion of the cylinder 42 of a fluid pressure motor M. The cylinder 42 is slid-

ably supported adjacent its rear end for movement toward and away from the rail 1 within a recess 43 which is formed in a tie-plate 21 secured to the crosstie 3, and has reciprocably mounted therein a piston 44 which drives a piston rod 45. The piston rod 45 extends through a cylinder head 46, and is secured at its free end to the brake beam 5 of the braking bar A² by means of nuts 45^a. The piston 44 is constantly biased to a retracted position within the cylinder 42 by means of a compressed coil spring 47 which surrounds the piston rod between the piston 44 and the cylinder head 46, and the piston is arranged to be at times moved to a projected position, in opposition to the bias of the spring 47, by admitting fluid pressure to the cylinder 42 through an inlet pipe 48. It will be apparent that movement of the piston 44 within the cylinder 42 will act through the piston rod 45 and the eyebolts 40 to move the braking bars toward or away from each other, according as the piston is moved toward its projected position or its retracted position, and the parts are so proportioned that when the piston is moved to its projected position, the braking bars will be moved toward each other to such positions that the spacing between the brake shoes will be less than the width of car wheels traversing rail 1. Whereas, when the piston is moved to its retracted position, the braking bars will be moved away from each other to such positions that the distance between the brake shoes will be greater than the width of car wheels traversing rail 1. Surrounding the eyebolts 40 between the rail 1 and the brake beam 5 of the braking bar A² are coil springs 49 which constantly bias the braking bar A² toward the right to a position in which depending stop lugs 50 which are provided on the brake beam engage stop screws 51 mounted in a bracket 52 secured to the crosstie 2 adjacent the outer side of the brake beam 5 of the braking bar A². The stop screws 51 each carry lock nuts 53, whereby the stop screws may be locked in adjusted positions. The stop screws are so adjusted that when the braking bar A² is engaging the stop screws 51, the brake shoe 4 of this braking bar will be out of the path of car wheels traversing rail 1, and that, when the braking bar A² is engaging the stop screws 51 and the piston 44 of motor M occupies its retracted position, the brake shoe 4 of the braking bar A¹ will occupy a position in which it is out of the path of car wheels traversing rail 1. The recess 43 in which the cylinder 42 of motor M slides is of such length, and the parts are so proportioned that when the piston 44 occupies its 55

projected position, and the cylinder 42 is engaging the rear wall 43^a of the recess 43, the braking bars A¹ and A² will then be held in the proper positions relative to the rail 1 to permit 5 a smooth entry of the wheels of cars between the braking bars.

The operation of the portion of the retarder thus far described is as follows: When fluid is exhausted from the cylinder 42 of motor M, piston 44 is held in its retracted position by the spring 47, and the braking bars and motor assembly as a whole are moved toward the right by means 10 of the springs 49 to the positions in which the stop lugs 50 engage the stop screws 51. Under 15 these conditions, due to the previously described proportioning of the parts, the brakeshoes of the braking bars are separated a distance which is greater than the width of the car wheels, and are so positioned with respect to the rail 1 that both 20 braking bars will be out of the path of car wheels traversing rail 1. It will be apparent, therefore, that when fluid is exhausted from motor M, the car retarder will not exert any braking force on cars passing through it. When, however, fluid 25 is supplied to motor M, the braking bars A¹ and A² will then be moved toward each other by the relative movement of the piston 44 and cylinder 42 to the positions in which the spacing between 30 the brake shoes 4 is less than the width of car wheels, and will be positioned relative to the rail 1 by engagement of the motor cylinder with the stop formed by the rear wall 43^a of the recess 43 in the tie-plate 27 in which the motor cylinder slides, and under these conditions, if a car enters 35 the retarder the wheels of the car will force the braking bars apart, which movement of the braking bars will compress the fluid in the motor cylinder, and will thus cause the braking bars to be held into frictional engagement with the car wheels by a biasing force which depends upon 40 the pressure of the fluid in the motor. It follows, therefore, that when fluid is admitted to motor M, the retarder will act to retard the speed of cars passing through the retarder. When the 45 braking bars of the retarder have been moved to their closed positions by admitting fluid to motor M, and it is desired to move them to their open positions, the fluid which was previously supplied to motor M is exhausted to atmosphere, whereupon the springs 47 and 49 will immediately act to 50 restore the braking bars to their open or non-braking positions.

With the retarder constructed in the manner thus far described, it will be apparent that due 55 to the fact that the points at which the braking bars engage the car wheels are located some distance above the eyebolts 40, a couple of forces will be exerted on the braking bar A¹ which will tend to rotate this braking bar in a counterclockwise direction, and a similar couple of forces will be 60 exerted on the braking bar A² which will tend to rotate this latter braking bar in a clockwise direction. These couples tend to bend the eyebolts 40, and are therefore undesirable, and in accordance 65 with my present invention I provide suitable means for counteracting the turning forces caused by these couples. As here shown, these means comprise two similar U-shaped brackets 23, one of which is secured adjacent its open end to the 70 brake beam 5 of the braking bar A¹ by means of bolts 24 which pass through the one leg of the brake beam and through upstanding lugs 25, one of which is formed on each leg of the brackets; and the other of which brackets is secured 75 adjacent its open end to the brake beam 5 of the

braking bar A² in the same manner that the first mentioned bracket is secured to the other brake beam. The outer portion of each bracket is slidably supported on a tie-plate 27 secured to the associated tie 3, and the inner ends of the brackets 5 are provided with offset portions 23^a which extend underneath the base flanges of the rail 1 on opposite sides of the rail support 2.

With the bracket 23 secured to the braking bars in the manner just described, it will be obvious 10 that when the brake shoes are engaging a car wheel, the couple or turning forces produced in the braking bars by the reaction of the wheels against the brake shoes 4 will be counteracted by engagement of the brackets with the tie-plates 15 27 and with the bottom of the rail, and as a result, any motion of the braking bars will be limited to a straight sliding motion toward and away from the rail. This is very desirable, not only because it prevents the eyebolts from becoming 20 bent, but also because it reduces lost motion, which, in turn, increases the retardation which can be obtained from the retarder and reduces the amount of wear of the parts.

It should be noted that adjustments to compensate 25 for wear of the brake shoe 4 of the braking bar A² may be made by turning the nuts 45^a which fasten the piston rod 45 to the brake beam 5 of this braking bar, while adjustments to compensate for wear of the brake shoe 4 of the braking bar A¹ may be made by turning the nuts 40^a which fasten the eyebolts 40 to the brake beam 5 of this latter braking bar.

Although I have herein shown and described 30 only one form of railway braking apparatus embodying my invention, it is understood that various changes and modifications may be made 35 therein within the scope of the appended claims without departing from the spirit and scope of my invention.

Having thus described my invention, what I 40 claim is:

1. Railway braking apparatus comprising a first and a second braking bar each comprising a brake shoe secured to a brake beam and each 45 extending parallel to a track rail on opposite sides of the rail, a bolt extending through clearance holes in both brake beams and a clearance hole in the rail web in such manner that the braking bars are slidably supported for movement toward 50 and away from the rail by means of said bolt, means for adjustably securing said bolt to the one brake beam, a fluid pressure motor connected 55 with said bolt and with the other brake beam and effective when supplied with fluid pressure 60 for biasing the braking bars toward the track rail to positions in which the brake shoes will frictionally engage the opposite side faces of car wheels traversing said rail, and means for limiting the movement of said braking bars toward 65 the track rail.

2. Railway braking apparatus comprising a first and a second braking bar each comprising a brake shoe secured to a brake beam and each 65 extending parallel to a track rail on opposite sides of the rail, a bolt extending through clearance holes in both brake beams and a clearance hole in the rail web in such manner that the braking bars are slidably supported for movement toward and away from the rail by means 70 of said bolt, means for adjustably securing said bolt to the one brake beam, a fluid pressure motor connected with said bolt and with the other brake beam and effective when supplied with fluid pressure for biasing the braking bars 75

5 toward the track rail to positions in which the
brake shoes will frictionally engage the oppo-
site side faces of car wheels traversing said rail,
means for limiting the movement of said brak-
ing bars toward the track rail, and a bracket se-
cured to each braking bar for preventing the
braking bars from tipping due to the couple of
forces which are exerted on them when they
are engaging car wheels, each said bracket being
10 slidably supported at one end and being pro-
vided at the other end with means which slid-
ably engage the underside of the track rail.

15 3. Railway braking apparatus comprising a
first and a second braking bar extending par-
allel to a track rail on opposite sides of the rail,
two bolts extending with clearance through holes in
the rail web in such manner that said braking bars
are slidably supported by means of said bolts
20 for movement toward and away from the rail,
means for adjustably securing one end of each
bolt to the one braking bar, a fluid pressure
motor having a cylinder connected with the
other end of each bolt, a piston reciprocably
25 mounted in said cylinder, and a piston rod con-
nected at one end to said piston and adjustably
secured at the other end to said second braking
bar, the parts being so proportioned that move-
ment of said piston from its retracted to a pro-
30 jected position will move said braking bars to
positions in which they will frictionally engage
the opposite side faces of each car wheel trav-
ersing the track rail.

35 4. Railway braking apparatus comprising a
first and a second braking bar extending par-
allel to a track rail on opposite sides of the rail,
two bolts extending with clearance through holes in
the rail web in such manner that said braking bars
40 are slidably supported by means of said bolts
for movement toward and away from the rail,
means for adjustably securing one end of each
bolt to the one braking bar, a fluid pressure
motor having a cylinder connected with the other
45 end of each bolt, a piston reciprocably mounted
in said cylinder, and a piston rod connected at
one end to said piston and adjustably secured
at the other end to said second braking bar,
the parts being so proportioned that movement
50 of said piston from its retracted to a projected
position will move said braking bars from pos-
itions in which the braking bars are out of the
path of car wheels traversing the track rail to
positions in which they will frictionally engage

the opposite side faces of each car wheel trav-
ersing the track rail.

5 5. Railway braking apparatus comprising a
first and a second braking bar extending par-
allel to a track rail on opposite sides of the 5
rail, two bolts extending with clearance through
holes in each braking bar and aligned holes in
the rail web in such manner that said braking
bars are slidably supported by means of said
bolts for movement toward and away from the 10
rail, means for adjustably securing one end of
each bolt to the one braking bar, a fluid pres-
sure motor having a cylinder connected with the
other end of each bolt, a piston reciprocably
15 mounted in said cylinder, a piston rod connected
at one end to said piston and adjustably se-
cured at the other end to said second braking
bar, the parts being so proportioned that move-
ment of said piston from its retracted to a pro-
20 jected position will move said braking bars 20
from positions in which the braking bars are
out of the path of car wheels traversing the rail
to positions in which they will frictionally en-
gage the opposite side faces of each car wheel
25 traversing the rail, and a spring in said cylinder
for biasing the piston to its retracted position.

30 6. Railway braking apparatus comprising a
first and a second braking bar extending par-
allel to a track rail on opposite sides of the rail,
two bolts extending with clearance through 30
holes in each braking bar and aligned holes in
the rail web in such manner that said braking
bars are slidably supported by means of said
bolts for movement toward and away from the
rail, means for adjustably securing one end of 35
each bolt to the one braking bar, a fluid pres-
sure motor having a cylinder connected with the
other end of each bolt, a piston reciprocably
mounted in said cylinder, a piston rod connected
40 at one end to said piston and adjustably se-
cured at the other end to said second braking
bar, the parts being so proportioned that move-
ment of said piston from its retracted to a pro-
jected position will move said braking bars from
45 positions in which they are out of the path of
car wheels traversing the track rail to positions
in which they will frictionally engage the oppo-
site side faces of each car wheel traversing the
track rail, a spring in said cylinder for biasing
50 the piston to its retracted position, and means
effective when said piston occupies its retracted
position for moving the braking bars to prede-
termined positions relative to said rail.

HAROLD C. CLAUSEN.
